UNITED STATES PATENT OFFICE.

ARMAND KARRER, OF ST. JOSEPH, MISSOURI.

THREAD-CUTTER.

No. 853,979.

Specification of Letters Patent.

Patented May 21, 1907.

Application filed June 6, 1905. Renewed April 13, 1907. Serial No. 368,086.

To all whom it may concern:

Be it known that I, ARMAND KARRER, a citizen of the United States, residing at St. Joseph, in the county of Buchanan and State 5 of Missouri, have invented certain new and useful Improvements in Thread-Cutters; and I do declare the following to be a full, clear, and exact description of the invention, such as will enable others skilled in the art to 10 which it appertains to make and use the same, reference being had to the accompanying drawings, and to the letters and figures of reference marked thereon, which form a part of this specification.

15 My invention relates to an improved cutter particularly adapted for clipping or cutting thread. My object is to provide a device operated by the thumb and adapted to be carried by the hand as long as needed 20 without interfering with the free use of the fingers thereby especially suiting it to the use of the large number of operators upon sewing machines who are employed in manufactories for clothing and other articles.

25 I attain my object by the mechanism illustrated in the accompanying drawing, in which—

Figure 1 is a top view of the thread cutter shown in position on a hand, with blades 30 parted, a thumb grip and screw pivot and a lug and slot which hold the blades open or shut in the desired position; Fig. 2 illustrates a double loop by which the cutter is carried on the fingers; Fig. 3 is a bottom view of the 35 cutter showing the angle at which the double loop for fingers is set on the handle of the bottom blade; Fig. 4 is a top view of the cutter showing the position of the lug in the slot when the blades are closed; Fig. 5 is a 40 top view of same showing position at which the lug engages with the slot to prevent the opening of blades beyond a clipping position; Fig. 6 is a top view of the bottom blade showing the loop and lug thereon; Fig. 7 is a top 45 view of the top blade showing its thumb grip and slot; Fig. 8 is a perspective of the device showing the precise form of the loop; Fig. 9 is an end view of the same; Fig. 10 is a detail of the screw pivot; Fig. 11 is a horizontal 50 section through the pivot and lug, and Fig.

12 is a perspective view showing the lug and slot in one of the handles.

Similar letters refer to similar parts in the several views.

The manner in which a thread cutter is 55 held is illustrated by hands A A.

B is the top and B' is the bottom blade of a thread cutter the respective handles C and C' being at slight angles with their respective blades, as shown in Figs. 1 and 3. These 60 handles with their blades are held on each other by a screw pivot D which permits them to be taken apart readily for sharpening the blades.

On the top blade there is a thumb grip E, 65 this grip consists of opposite flanges d d set adjacent to the cutting part of the blade and which slope upward at a suitable width apart to receive the thumb that it may carry the blade back and forth for clipping or cutting 70 the threads.

At the end of handle C' there is a lug F which is adapted to engage with a slot H in the end of handle C, said slot being of a width to permit a play of the lug therein that 75 will allow the blades to open to a width substantially as shown, and that will also prevent the blades passing over each other beyond their normal closed position.

I is a double loop to receive the ring and 80 little fingers by which the thread cutter is held in position on the hand. It is adapted to set between the finger and knuckle joints and bears outward at an angle, as shown in Fig. 3, that will hold the device in a position that 85 will conform it to the position of the fingers when the hand is closed for cutting a thread.

This thread cutter does not in any way interfere with the free use of the fingers and may therefore be retained on the hand without interfering with the work of the operator and be ready at any instant for the thumb to engage with the thumb grip and close the blade, thereby cutting the thread or other article. 95

What I claim as my invention, and desire to secure by Letters Patent, is

1. In a thread cutter the combination of two blades pivotally connected, one of said blades having thumb engaging flanges, han- 100

dles on the blades set at an angle thereto, a slot in one handle and a lug in the other handle to enter said slot and limit the movement of the blades.

- 5 2. A thread cutter consisting of two blades, pivotally connected handles therefor one provided with a slot at its lower end, the other having a lug to enter said slot and a

loop to receive the finger as for the purpose set forth.

In testimony whereof, I affix my signature, in presence of two witnesses.

ARMAND KARRER.
